JAMES H. DEAN, OF LUDINGTON, MICHIGAN, AND GEORGE W. BAKER, OF CHICAGO, ILLINOIS, ASSIGNEES, BY MESNE ASSIGNMENTS, TO UNITED STATES GYPSUM COMPANY, OF CHICAGO, ILLINOIS, A CORPORATION OF ILLINOIS

BELT TIGHTENER FOR MACHINES FOR EXPANDING METAL

Application filed March 5, 1926. Serial No. 92,539.

In Letters Patent issued April 6, 1909, No. 917,715, to Lewis E. Curtis, assignor, to Breckenridge Jones, trustee, there is shown and described a machine for expanding sheet metal which has been previously cut or slotted, that employs diverging expander arms with feeding means, consisting of opposing chains in each arm, one above and one below the sheet, and moving with it and gripping its unexpanded margins, one of each pair of chains being arranged parallel to the line of feed, and the other one of each pair being arranged at an angle to such line.

In the operation of these machines the wear of the pivotal connections between the links causes the chains to become lengthened and loose upon their carrying and driving sprockets. The looseness of the chains interferes with the proper feeding of the sheets. It has been attempted to remedy this by placing the sprocket at one end of each chain upon an eccentric bearing, but this means of tightening causes a separation of the opposing chains near their ends and this separation of the chains interferes with the proper feeding of the sheets.

Our improvement is designed to provide a satisfactory means for tightening the feeding chains of this Curtis machine without separating the opposing chains or otherwise interfering with their proper feeding function.

To this end our invention consists in the combination with the expander arm of a machine of the type indicated, of a pivoted arm carrying a roll or sprocket wheel arranged to engage the inner surface of the feeding belt at the non-feeding or idle side thereof, and means for adjusting the position of said arm so as to bring the roll or sprocket in contact with the inner surface of the belt, thereby moving the same and taking up all slack or lost motion that may be occasioned in the pivotal connections of the chain.

The invention consists further in the constructions and combination hereinafter described and particularly pointed out in the claims.

In the accompanying drawings forming a part of this specification,

Figure 1 is a side elevation of an arm of the

Curtis machine of the type specified, with one of the side plates removed and with the parts of the tightener device partly broken away;

Figure 2 is a detail horizontal section on line 2—2 of Figure 1; and

Figure 3 is a transverse section on line 3—3 of Figure 1.

In the drawing the reference numerals 4—4 indicate the side plates of the expander arm, said plates being connected by the bolts 5 and forming, with said connecting bolts, the frame of said arm. One of said plates is provided with a longitudinally extending rib 6, against the edge of which the other plate bears, said rib forming a spacing means between said plates. Mounted between said plates are the sprocket wheels 7 and 8 upon which the feeding chain 9 is mounted. These parts of the structure are all substantially as shown in the drawings of said Curtis Patent No. 917,715.

Arranged between said plates and mounted upon a fixed stud or bolt 10 (see Figure 3) is an arm 11 carrying a roll or sprocket wheel 12 mounted on a pin 20 and arranged to engage the inner surface of the chain 9 at the non-feeding or idle side thereof. Said arm 11 is recessed thereby forming a pair of short arms 13 projecting from the main part of the arm and forming therewith a bell crank lever, pivotally supported on the bolt 10. A threaded eye-bolt 14 is pivoted between the arms 13 upon a pin 15. The threaded portion of said bolt passes through a cross-bar 16 pivotally supported in the side plates 4 (see Figure 2). Nuts 17 are arranged upon said threaded bolt on either side of said bar 16.

In operation, as the connections of the belt become loose, the nuts 17 upon the bolt 14 are adjusted so as to move the roll or sprocket wheel 12 against the inner surface of the belt to take up the slack or lost motion occasioned by the wear of the belt connections. These nuts may be adjusted as often as found necessary to keep the feeding belt tight and in proper condition for feeding the metal sheets passing between the opposing surfaces of said belts. A sprocket wheel 12 or

a plain surfaced roll or wheel may be employed with substantially the same results.

By placing the adjusting device within the belt and between the side plates 4—4 it is 5 practically sealed within the expander arm and thus dirt or foreign material is prevented from accumulating thereon and interfering with the operation of said device.

The details of the construction may be varied without departing from our invention.

10 We claim as our invention:

1. An expander arm comprising two side plates, sprocket wheels between the plates having journals in the plates, a chain connecting the sprocket wheels and having one run as a working element extending beyond the plates at one side, an arm pivotally supported by both plates and having a sprocket wheel engaging the non-working run of the 15 chain at the inner side, and means pivotally connected with said arm and adjustably mounted between the plates and runs of the sprocket wheel to move the arm, all chain-tightening elements lying between the runs of the chain and being enclosed by the plates.

2. An expander arm comprising two side plates, a pair of sprockets arranged between the plates, and having journals in said plates, a chain connecting the sprockets and having one run as a working element extending beyond the edges of the plates, and means for 20 tightening the chain, said means lying between the runs of the chain, and between the plates and being pivotally supported by both 25 of the plates, and including a sprocket wheel engaging the inner side of the non-working run of the chain.

3. An expander arm comprising two side plates a pair of sprocket wheels journaled in 30 and crosswise of the plates adjacent opposite ends thereof, a chain connecting the sprocket wheels and having one run as a working element extending beyond the plates at one side, an arm pivotally supported by both plates, a sprocket wheel journaled upon 35 the arm to engage the non-working run, a cross bar journaled by and between the plates and chain, a bolt loosely traversing the cross bar and pivotally connected to the arm adjacent the pivotal point of the arm with the 40 plates, the pivotal point of the bolt with the arm lying intermediate the pivotal point of the arm with the plates and the non-working run.

55 In witness whereof we have hereunto set our hands this 11th day of February, 1926.

JAMES H. DEAN.
GEO. W. BAKER.
